UNITED STATES PATENT OFFICE.

SIDNEY Y. BALL, OF CLEVELAND, OHIO, ASSIGNOR TO THE WEBB C. BALL WATCH COMPANY, OF CLEVELAND, OHIO, A CORPORATION OF OHIO.

DESIGN FOR A BOW-SOCKET FOR WATCHES.

40,668.

Specification for Design.

Patented May 3, 1910.

Application filed December 20, 1909. Serial No. 534,218. Term of patent 14 years.

To all whom it may concern:

Be it known that I, SIDNEY Y. BALL, a citizen of the United States, and a resident of Cleveland, county of Cuyahoga, and State of Ohio, have invented a new, original, and ornamental Design for Bow-Sockets for Watches, of which the following is a specification, reference being had to the accompanying drawing, forming part thereof.

In said annexed drawing:—the figure is a

plan of a bow socket showing my new design.

I claim:—

The ornamental design for a bow socket for watches, as shown.

SIDNEY Y. BALL.
